DESIGN FOR A SHOE

Albert F. Bancroft, Newton, Mass., assignor to
Bancroft Walker Co., Waltham, Mass., a cor-
poration of Massachusetts

Application October 25, 1934, Serial No. 53,750

Term of patent 3½ years

To all whom it may concern:

Be it known that I, Albert F. Bancroft, a citizen of the United States, residing at Newton, in the county of Middlesex and Commonwealth of Massachusetts, have invented a new, original, and ornamental Design for a Shoe, of which the following is a specification, reference being had to the accompanying drawing, forming a part thereof, in which

Fig. 1 is a view in side elevation of a shoe showing my design; and

Fig. 2 is a plan view of the shoe.

The ornamental effect of my design resides in an opening of oval shape located in the forepart

of the shoe adjacent to the throat of the vamp and a front strap arranged with its forward end projecting within the contour of the opening, the strap, vamp and counter of the shoe exhibiting a straight line of ornamental stitching with a wavy line of stitching weaving back and forth over it.

I claim:

The ornamental design for a shoe substantially as shown and described.

In testimony whereof, I have affixed my signature hereto.

ALBERT F. BANCROFT.
